SCOREKEEPING DEVICE

Elmer George, St. Louis, Mo.

Application March 4, 1940, Serial No. 322,057

3 Claims. (Cl. 235—120)

This invention relates to score-keeping devices for use in keeping score when playing such games as ping pong, badminton, etc., its principal object being to relieve the players from the burden of keeping score from memory, and also from the necessity of remembering when it is time to change serve. As is well known to those who play games of this kind, the scores and serves are often not accurately kept, due to the fact that in the excitement of the game the players lose sight of these points, and after several plays it is difficult to recall them from memory. My device not only indicates the number of points scored by a player, but also indicates the number of serves. Each time a point is made by a player he indicates it on the face of the device by merely pulling a cord connected with the device, which action simultaneously indicates a serve, so that by glancing at the device it can be instantly ascertained at any time how many serves have been made and whether it is time to change serve, and also how many points have been scored by the players. The device can be used to equal advantage, whether individuals or teams are playing one another.

Fig. 1 is a view illustrating my device suspended in operating position on a wall near a table on which a game is being played, showing the pull cords for operating the device.

Fig. 2 is an enlarged front view, showing the hands for indicating the number of points and serves which have been made by the players.

Fig. 3 is a rear view of my device with the rear cover plate removed therefrom, illustrating the operating mechanism.

Fig. 4 is an enlarged, cross-sectional view taken on line 4—4, Fig. 3.

Fig. 5 is an enlarged, cross-sectional view taken on line 5—5, Fig. 3.

While it is to be understood that my score-keeping device can be adapted for use in playing various games, for the sake of simplifying this specification I will describe an adaptation for use when playing a game in which twenty-one points constitute a game and serve is changed after five serves, and in which two players are engaged.

In the drawing I have illustrated my device as comprising mechanism enclosed within a housing H having a rear cover plate R, and a front face A provided with three indicating hands mounted at the center of said face for rotation in a clockwise direction. The hands 1 and 2 indicate the number of points made by the players, while the hand 3 indicates the number of serves,

and the hand 3 is located intermediate of the hands 1 and 2 for a reason to be hereinafter set forth. A series of numerals B, running from "1" to "20", are consecutively arranged clockwise near the outer circumference of the face A for the purpose of indicating the number of points and serves scored, and the hand 3 is provided with an aperture 4 at its free end so that as the hand 3 is rotated the aperture 4 will pass over the numerals B, permitting any one of said numerals over which the aperture 4 comes to rest to be observed through said aperture. On the face A adjacent its circumference and between said circumference and the series of numerals B there is painted a black section X extending from "5" to "9", inclusive, of said numerals, and a similar black section Y is painted between the circumference of the face A and the numerals B extending from "14" to "19", inclusive, of said numerals, the purpose of which will be explained later.

The parts thus far described are illustrated in Fig. 2, and the indicating hands 1, 2, and 3 are connected with operating mechanism in the interior of the device in a manner to be presently set forth.

Referring now to the mechanism within the housing for operating the hands 1, 2, and 3: A rotatable pin 5 extending through an opening (not shown) in the center of the face A is enclosed within a rotatable sleeve 6, and said sleeve 6 is enclosed within a rotatable sleeve 7, the sleeves 6 and 7 being rotatable with respect to each other as well as with respect to the pin 5, and the pin 5 projecting slightly beyond the sleeve 6, while the sleeve 6 projects slightly beyond the sleeve 7. The end of the pin 5 which extends outwardly through the opening in the center of the face A is attached to the indicating hand 2, the sleeve 6 is attached at its outwardly extending end to the hand 3, and the sleeve 7 is attached at its outwardly extending end to the hand 1. The end of the pin 5 which extends into the housing has attached thereto a ratchet wheel 8. The portion of the sleeve 6 which extends into the housing is slightly shorter than the pin 5 and has attached thereto at its end a ratchet wheel 9, and the portion of the sleeve 7 which extends into the housing is slightly shorter than the sleeve 6 and has attached thereto at its end a ratchet wheel 10. It will thus be seen that the hand 2 is connected to the ratchet wheel 8 through the medium of the pin 5, the hand 3 is attached to the ratchet wheel 9 through the medium of the sleeve 6, and the hand

1 is attached to the ratchet wheel 10 through the medium of the sleeve 7; so that when the ratchet wheel 8 is rotated the hand 2 is correspondingly rotated; when the ratchet wheel 9 is rotated the hand 3 is correspondingly rotated; and when the ratchet wheel 10 is rotated the hand 1 is correspondingly rotated. The pin 5 and the sleeves 6 and 7 are held in place at the center of the face A by a surrounding, stationary, tubular member 11 (Fig. 4) said tubular member 11 being soldered or otherwise secured to the inner side of the face A and extending outwardly through the opening in the center of the face A, and being of a diameter sufficiently large to permit rotation of the sleeve 7 therein. The pin 5 and sleeves 6 and 7 extend beyond the tubular member 11 at both of its ends.

A plate 12, provided with an elongated slot 13, is positioned between the ratchet wheels 8 and 9, the elongated slot 13 permitting both rotatable and up and down movement of said plate 12 about the pin 5, and a lug 14 projecting through and beyond both faces of the plate 12 is adapted to engage the teeth of both the ratchet wheels 8 and 9 simultaneously. A plate 15, provided with an elongated slot 16 similar to the slot 13, is positioned between the ratchet wheels 9 and 10 for movement about the sleeve 7, and a lug 17 projecting through and beyond both faces of the plate 15 is adapted to engage the teeth of both the ratchet wheels 9 and 10 simultaneously. The elongated slots 13 and 16 permit an up and down movement of the lugs 14 and 17, respectively, so that said lugs may ride over the teeth of the ratchet wheels 8, 9, and 10. The plates 12 and 15 are provided with perforations 18 and 19, respectively, for a purpose to be hereinafter set forth.

A coiled wire spring 20 is secured at one of its ends to the inner face of the front wall of the housing H, as at 21, and the opposite end of said spring 20 is hooked into the perforation 18 in the plate 12. A pull wire 22 is also hooked into the perforation 18, passed through a tubular guiding member 23, and through a perforation 24 in the rim of the housing H, and secured to a loop member C to which a pull cord D is attached. A similar coiled wire spring 25 is secured at one of its ends to the inner face of the front wall of the housing H, as at 26, and has its opposite end hooked into the perforation 19 in the plate 15. A pull wire 27 is also hooked into the perforation 19, passed through a guiding member 28 and upwardly through a perforation 29 in the rim of the housing, after which it is secured to a loop member E to which a pull cord F is attached. Stop members 29 and 30 check the forward and backward movements, respectively, of the plate 12, and similar stop members 31 and 32 check the forward and backward movements, respectively, of the plate 15.

A stationary member 33 (Figs. 3 and 5) fastened to the inner face of the front wall of the housing H is provided with three resilient fingers 34, 35, and 36, which normally engage the teeth of the ratchet wheels 8, 9, and 10, respectively. When the plates 12 and 15 have been released from a forward pull and the springs 20 and 25 exert a retractive pull on said plates, the fingers 34, 35, and 36 will engage the next adjacent tooth on each of said ratchet wheels, respectively, thus preventing the ratchet wheels from being retracted.

When the device is to be used for keeping score during the playing of a game, it is pref-

erably suspended from a wall near the playing table, as illustrated in Fig. 1. For the purpose of this description we will assume that the game is being played by two individuals, who we will designate as White and Black. The indicating hand 1 of the device is painted black and will keep score for the player Black, while the indicating hand 2 is painted white and will keep score for the player White. The hand 3 is painted any other color and, as stated before, indicates only the number of serves that have been made.

Supposing now that the player White has served and made a point. He pulls the cord D attached to the loop C, which exerts a pull on the pull wire 22 which, being hooked into the perforation 18 in the plate 12, pulls said plate a sufficient distance so that the lug 14, which is normally in engagement with a tooth on each of the ratchet wheels 8 and 9, will move forward and engage the next adjacent tooth on each of said ratchet wheels. The stop member 30 acts to check the plate 12 when the lug 14 has engaged said next adjacent tooth, whereupon the pull is released and the coil spring 20 exerts a retractive pull on said plate 12 (being hooked thereto through the perforation 18) to bring the plate 12 back to its normal position, and the fingers 34 and 35 serve to keep the ratchet wheels from being retracted more than one tooth by the spring 20.

As has been heretofore pointed out, the ratchet wheel 8 is connected to the hand 2 through the medium of the rotatable pin 5, and the movement of the hand 2 and ratchet wheel 8 are so synchronized that when the ratchet wheel moves the distance of one tooth the hand moves forward one point, indicated on the numerals B on the face A. Since the hand 3 is connected to the ratchet wheel 9 through the medium of the rotatable sleeve 6, and since the lug 14 engages the teeth of ratchet wheels 8 and 9 simultaneously, it will be seen that said hand 3, indicating a serve, has also moved forward one point.

When the player Black scores a point he pulls the cord F attached to the loop E, which exerts a pull on the wire 27 which, being hooked into the perforation 19 in the plate 15, pulls said plate a sufficient distance so that the lug 17, which is normally in engagement with a tooth on each of the ratchet wheels 9 and 10, will move forward and engage the next adjacent tooth on each of said ratchet wheels. The stop member 32 acts to check the plate 15 when the lug 17 has engaged said next adjacent tooth, whereupon the pull is released and the coil spring 25 exerts a retractive pull on said plate 15 (being hooked thereto through the perforation 19) to bring the plate 15 back to its normal position, and the resilient fingers 35 and 36 serve to keep said ratchet wheels 9 and 10 from being retracted by the spring 25.

The ratchet wheel 10 is connected to the hand 1 through the medium of the rotatable sleeve 7, as heretofore pointed out, and the movement of the hand 1 and the ratchet wheel 10 are so synchronized that when the ratchet wheel moves forward the distance of one tooth, the hand moves forward one point indicated on the numerals B on the face A. As before said, the hand 3 is connected to the ratchet wheel 9 through the medium of the rotatable sleeve 6, and since the lug 17 engages the teeth of ratchet wheels 9 and 10 simultaneously, it will be

seen that said hand 3, indicating a serve, has also moved forward one point. The movement of the ratchet wheel 9 and the hand 3 are also synchronized, so that when the ratchet wheel 9 moves forward the distance of one tooth the hand moves forward one point. From the above description it will be clear that the forward movement of the hand 3 takes place simultaneously with the forward movement of either the hand 1 or the hand 2.

The player White serves five times, and each serve is indicated by the hand 3. When he has served five times the aperture 4 in the hand 3 will be positioned over the "5" in the series of numerals B opposite the beginning of the black section X, thus indicating that it is time for the serve to change, and the player Black will then serve five times, until the hand 3 has moved away from the black section X and is stationed with its aperture over the "10" in the series of numerals B, and this alternation will be continued, the service of the player Black being indicated while the hand is pointing to numerals B adjacent the black sections X and Y, and the serves of the player White being indicated while the hand 3 is pointing to numerals adjacent the intermediate, unpainted sections adjacent the circumference of the face A. Thus, a mere glance at the device will enable the players to ascertain which player should be serving and how many more serves he has until it is time to change serve, and also how many points each player has scored.

While I have described my device as having a circular face A with the numerals B arranged clockwise thereon, it is to be understood that it is not limited to this form but may take any other desired shape; for instance, the face A may be rectangular with the numerals B arranged thereon in a straight line.

I claim:

1. A score-keeping device for use in playing games in which players change serve upon reaching predetermined total scores, including a face bearing score indicia, a pair of indicating elements and a totalizing element support for movement with respect to said face, and operating means for moving said indicating elements and said totalizing element, said operating means comprising two independent mechanisms one for

actuating one of said indicating elements and said totalizing element, the other said mechanism for actuating its associated indicator element and the totalizing element, a predetermined distance, and additional arcuately arranged indicia on said face defining a zone which cooperates with said totalizing element to indicate change of serve.

2. A score-keeping device for use in playing games in which the players change serve when a predetermined total score is attained, including a circular face bearing score indicia arranged near the circumference of said face, a pair of indicating elements and a totalizing element supported for movement with respect to said face, and operating means for moving said indicating elements and said totalizing element, said operating means comprising independent mechanisms one for actuating one of said two indicating elements and said totalizing element the other said mechanism for actuating its associated indicator element and the totalizing element a predetermined distance, and additional arcuately arranged indicia on said face which cooperates with said totalizing element to indicate change of serve.

3. A score-keeping device for use in playing games in which the players change serve when the score reaches a predetermined total, including a circular face bearing score indicia arranged near the circumference of said face, a pair of indicating hands and a totalizer hand supported for movement with respect to said face, said totalizer hand having an aperture at its free end through which said indicia may be observed, and operating means for moving said indicating hands and said totalizer hand, said operating means comprising two independent mechanisms one for actuating one of said indicating hands and said totalizer hand, the other of said mechanisms for actuating its associated indicator element and the totalizer hand a predetermined distance, and oppositely disposed lines one-quarter the length of the circumference of said face painted on said face adjacent its circumference adapted to indicate in connection with the aperture in said totalizer hand when the players should change serve.
